UNITED STATES PATENT OFFICE.

ALEXIS R. PRIBIL, OF DETROIT, MICHIGAN, ASSIGNOR TO PENBERTHY INJECTOR COMPANY, OF DETROIT, MICHIGAN, A CORPORATION OF MICHIGAN.

AUTOMATIC CELLAR-DRAINER.

1,116,481.

Specification of Letters Patent. Patented Nov. 10, 1914.

Application filed April 18, 1912. Serial No. 691,617.

To all whom it may concern:

Be it known that I, ALEXIS R. PRIBIL, a citizen of the United States of America, residing at Detroit, in the county of Wayne 5 and State of Michigan, have invented certain new and useful Improvements in Automatic Cellar-Drainers, of which the following is a specification, reference being had therein to the accompanying drawings.

10 The invention relates to an automatic drainer for cellars, sewers and other excavations arranged to discharge water noiselessly therefrom without attention by the user, the parts being so disposed as to be 15 accessible for repair or replacement and being otherwise arranged to combine simplicity with accuracy of operation.

The invention consists in the matters hereinafter set forth and more particularly 20 pointed out in the appended claim.

In the drawings, Figure 1 is a view in vertical section of an apparatus that embodies features of the invention; and Figs. 2 and 3 are views in section showing a 25 modification of an ejector.

As herein shown an ejector casing 1 has a pressure inlet arm 2 opening into a conical throat 3 with a discharge outlet nipple 4 to which a suitable drain pipe 5 may be connected. A suction nozzle 6 is removably secured in the casing with its jet mouth concentrically within the throat 3. A suction pipe 7 is connected to this nozzle. The lower end or mouth of the suction pipe is suitably 35 secured in an opening of a dome 8 on a cage 9 that may form a foot rest for the drainer and at any rate has an apertured side wall as a strainer. An outwardly closing check valve may be placed in this cage and may be 40 of any suitable design. As shown herein an annular valve seat 10 is sealed by a vertically movable closure 11 held in a depending stem 12 that reciprocates in a guide bushing 13 of the cage. Stop pins 14 may limit the upward movement of the closure.

A float operated valve controls the flow through the inlet arm 2. This may be of any type, but preferably, consists of a casting 15 having a pair of aligned valve seats 16 with a double flanged closure 17 thereon,

this closure being arranged to have a balanced action. A stem 18 depending from the closure, passes through a suitable packing gland 19 and a guide bushing 20 in a depending arm 21 of the casing. A float 28 has 55 a central guide sleeve 22 loosely reciprocable on the stem, adjustable stop collars 23 limiting its movement.

In Figs. 2 and 3 a modification of the ejector is shown in which the exhaust opening 24 is directly in line with a jet nozzle 25 that is supplied through a pressure inlet 26, and is disposed in the interior of the casing in substantial alinement with the suction inlet 27 and the passage or interior of the casing that connects this suction passage with the outlet 24. In both constructions the jet nozzle, either suction or pressure, is removable and interchangeable with other jet nozzles to vary the proportions and consequent 70 capacity of the ejector, or to meet different conditions or requirements of service. When the water level in the place in which the drainer is inserted, has reached the level sufficient to cause the float to raise the stem, 75 the ejector at once proceeds to draw water through the suction pipe owing to the aspirator action of the throat and suction nozzle and continues such action until the float has fallen sufficiently to close the valve. 80 The limited movement of the float independently of the valve allows the collection of a certain amount of water around the drainer before action results. While the foot valve or check in the suction pipe is an advantageous feature it need not be used unless desired.

Obviously, changes in the details of construction may be made without departing from the spirit of my invention and I do not 90 wish to limit myself to any particular form or arrangement of parts.

What I claim is:—

In an automatic drainer, the combination with an ejector having a drain pipe, and a 95 suction pipe vertically alining therewith, of a cage supporting said suction pipe, a pressure inlet arm carried by said ejector intermediate the ends thereof, a valve carried by said arm for admitting fluid under pressure 100

to said ejector, a depending guide arm carried by said valve, a valve stem extending through the arm of said valve into said valve to control the supply of fluid to said pressure inlet arm, adjustable stop collars on said valve stem, and a float movable upon said valve stem and limited in its movement thereon by said stop collars and adapted to

actuate said stem at a time determined by the volume of liquid to be drained.

In testimony whereof I affix my signature in presence of two witnesses.

ALEXIS R. PRIBIL.
